JIGGER

Howard A. Tarleton, Barrington, R.I., assignor to Gorham Corporation, Providence, R.I.

Filed Aug. 30, 1961, Ser. No. 66,546

Term of patent 14 years

(Cl. D44—9)

FIGURE 1 is a front elevational view of a jigger showing my new design;

FIGURE 2 is a top plan view;

FIGURE 3 is a sectional view on line 3—3 of FIGURE 2;

FIGURE 4 is an enlarged detail elevational view of one of the decorative elements shown in FIGURE 1;

FIGURE 5 is a sectional view on line 5—5 of FIGURE 4;

FIGURE 6 is an enlarged fragmentary detail view of the topmost heading; and

FIGURE 7 is an enlarged fragmentary detail view of the lower headings.

The decorative elements in FIGURES 1, 3, 4 and 5 appear on the front of the jigger only, and are shaded to indicate color contrast rather than specific color.

I claim:

The ornamental design for a jigger, as shown and described.
